UNITED STATES PATENT OFFICE.

THOMAS A. TOWN, OF WASHTUCNA, WASHINGTON.

WEEDING-MACHINE.

1,126,917.

Specification of Letters Patent. Patented Feb. 2, 1915.

Application filed December 23, 1912. Serial No. 808,456.

To all whom it may concern:

Be it known that I, THOMAS A. TOWN, a citizen of the United States, residing at Washucna, in the county of Adams, State 5 of Washington, have invented certain new and useful Improvements in Weeding-Machines, and I do hereby declare the following to be a full, clear, and exact description of the invention, such as will enable others 10 skilled in the art to which it appertains to make and use the same.

The present invention is directed to improvements in weeding machines, and has for its object to so construct a device of this 15 character that when the same is drawn across a field the weeds will be easily and quickly pulled.

A further object of the invention is to so construct a machine of this character that 20 during the movement of the same across the field the weed pulling rod will be rapidly rotated, thereby effectually removing the weeds.

A still further project of the invention is to 25 provide a novel means for rotating the weed pulling rod during the movement of the machine.

With these and other objects in view, this 30 invention resides in the novel features of construction, formation, combination and arrangement of parts to be hereinafter more fully described, claimed and illustrated in the accompanying drawing, in which:—

Figure 1 is a top plan view of the machine. Fig. 2 is a rear elevation. Fig. 3 is an end view. Fig. 4 is a sectional view on line 4—4 of Fig. 2. Fig. 5 is a similar view on line 5—5 of Fig. 1. Fig. 6 is a similar view on line 6—6 of Fig. 5.

The machine comprises a plurality of runners 1, the same being held in spaced parallel relation by brace bars 2, said brace bars being connected to the upper edges of the runners in any suitable manner. Connected to the 45 rear end of each runner 1 is a curved arm 3, said arm terminating in a sleeve 4 in which are rotatably mounted bearings 5, said bearings having their opposite ends threaded for the reception of the threaded bearing collars 50 6, the bores 7 of which are rectangular in cross section, and are adapted to receive the weed pulling shaft 8, which is also rectangular in cross section so that when rotary movement is imparted to the shaft 8 the bearings 5 will 55 rotate in the sleeves 4. By mounting the shaft 8 in this manner it is apparent that

the bearings 5 may be readily removed when worn and replaced with new ones.

Supported upon the brace bars 2 is a bar 9, to which is hingedly connected a rod 10, 60 the outer end of which is connected to a frame 11, said frame and rod being connected by brace bars 12. Rotatably supported by the frame 11 is a shaft 13, the same being also rotatably mounted in boxes 14 65 which are carried by the shaft 10. Fixed to which the shaft 13, and disposed between the side bars 15 of the frame 11 is a gear 16, which meshes with a gear 17 supported by the shaft 18, said shaft being journaled in the side 70 bars 15 of the frame. Connected to the inner end of the shaft 18 by the universal joint 19 is the outer end of the shaft 20, said shaft having a bore 21, rectangular in cross section 75 for slidably receiving the squared end of the shaft 22, the other end of which is connected to the weed pulling shaft 8 by the universal joint 23. Fixed to the outer end of the shaft 13 is a ground wheel 24 which imparts rotary movement to the shaft 13 80 when the machine is being drawn across the field, and through the medium of the gears 16 and 17 rotary movement is imparted to the shaft 8 through the medium of the shafts 20 and 22. 85

By hingedly connecting the bar 10 to the rod 9 the same may move vertically when the wheel 24 is traveling over uneven ground. Further it will be noted that by providing a slideable connection between the 90 shafts 20 and 22 that no strain will be imparted to the weed pulling shaft 8 when the rod 10 and frame 11 are moving vertically. The arms 3 are of sufficient length to hold the shaft 8 slightly below the lower edges 95 of the runners so that said shaft will rotate slightly under the ground level, thus insuring the removal of the weeds with their roots.

Connected to the forward ends of the runners 1 is a draw bar 25 to which is attached the whiffle-trees 26 so that draft animals may be attached to the machine for drawing the same across the field. 100

What is claimed is:—

1. In a machine of the class described comprising a plurality of runners, arms carried by the rear ends of the runners, a weed pulling shaft rotatably supported by the arms, bars for holding the runners in spaced parallel relation, a bar supported by the first named bars, a rod having its inner end 110

105

- hingedly connected to the bar, a frame carried by the outer end of the rod, a wheeled shaft supported by the frame and rod, a gear carried by said shaft, a shaft carried by the frame, a gear fixed to the shaft and arranged to mesh with the first named gear, the second named shaft being connected to the weed pulling shaft by slidably connected shafts, as and for the purpose set forth.
- 10 2. In a machine of the class described comprising a plurality of runners, a rotatable weed pulling shaft operatively connected to the runners, a frame, a rod rigidly connected thereto, means to hingedly connect the rod to the runners, a shaft rotatably supported by the frame and rod, a wheel connected to said shaft, means mounted in the frame and having operative connection with the wheel to rotate the weed pulling shaft, and a flexible connection between the weed pulling shaft and the operating means therefor.
- 15 3. In a machine of the class described comprising a plurality of runners, a rotatable weed pulling shaft operatively connected to the runners, a frame, a rod rigidly connected thereto, means to hingedly connect the rod to the runners, a shaft rotatably supported by the frame and rod, a wheel connected to said shaft, means mounted in the frame and having operative connection with the wheel to rotate the weed pulling shaft, and a flexible connection between the weed pulling shaft and the operating means therefor.

tion being formed in sections having relative sliding movement.

3. In a machine of the class described comprising a plurality of runners, a rotatable weed pulling shaft operatively connected to the runners, a frame, a rod rigidly connected thereto, means to hingedly connect the rod to the runners, a shaft rotatably supported by the frame and rod, a wheel connected to said shaft, means mounted in the frame and having operative connection with the wheel to rotate the weed pulling shaft, and a flexible connection between the weed pulling shaft and the operating means therefor.

In testimony whereof, I affix my signature, in the presence of two witnesses.

THOMAS A. TOWN.
